Assistant Examiner — D. Ryan Tisdale

(57) **CLAIM**

The ornamental design for an automobile as shown and described.

DESCRIPTION

1. Automobile

1.1 is a left, front perspective view of an automobile, embodying my new design;

1.2 is a right, rear perspective view thereof;

1.3 is a front elevation view thereof;

1.4 is a rear elevation view thereof;

1.5 is a left side elevation view thereof;

1.6 is a right side elevation view thereof; and

1.7 is a top plan view thereof.

The broken lines in the figures illustrate portions of the automobile that form no part of the claimed design.

1 Claim, 7 Drawing Sheets
